UNITED STATES PATENT OFFICE.

JOHN T. WELLS, OF NEWPORT, KENTUCKY, ASSIGNOR TO THE EDWARDS MANUFACTURING COMPANY, OF CINCINNATI, OHIO, A CORPORATION OF OHIO.

FILM-MAGAZINE FOR MOVING-PICTURE MACHINES.

1,175,851.

Specification of Letters Patent. Patented Mar. 14, 1916.

Application filed February 12, 1915. Serial No. 7,842.

To all whom it may concern:

Be it known that I, JOHN T. WELLS, a citizen of the United States, and residing at Newport, in the county of Campbell and State of Kentucky have invented a new and useful Improvement in Film-Magazines for Moving-Picture Machines, of which the following specification is a full disclosure.

My invention relates to a film reel mechanism for a moving picture machine, of the type disclosed in my pending application Serial No. 865,129, filed October 5, 1914.

The object of the invention is to provide a film reel mechanism suitable to the requirements of a machine adapted to take

print and project moving pictures.

More particularly, it is the object to provide film reels for winding and unwinding the film, which can easily and safely be handled without danger of spoiling the film by accidental exposure.

The features of the invention are more fully set forth in the description of the accompanying drawings, forming a part of this specification, in which:

Figure 1 is a side elevation, partly in section, of a complete camera. Fig. 2 is a top plan view partly in section of one end thereof showing the film magazine. Fig. 3 is a partial side elevation of the camera-box showing one of the magazine operating keys.

The camera-box consists of a base 1, and a box-like cover 2 secured thereto by suitable latches, one of which is shown in Fig. 3. Centrally disposed on the rear portion of said base are a pair of uprights 3, which serve as supports for the reel magazines 4, 5. These magazines are provided with pairs of eye-brackets 6, adapted to be threaded over the uprights 3, the brackets of the magazine 5 resting on collars 7 and the brackets of magazine 4 resting on brackets of magazine 5, as shown in Fig. 1. Each magazine is composed of two telescoping sections 8, 9, the section 8 having a spindle 10, which supports the film reel 11. It will be noted that the rear eye brackets 6 are longer than the forward brackets, thereby causing the line of film feed to converge toward the forward medial portion of the camera. Each of the sections 8, 9 is apertured peripherally, and when the machine is ready for operation, these apertures register to provide film openings 12, but when the magazines are to be removed from the

camera, these openings must be closed by partially rotating the section 9, to destroy said registry of the apertures. This is accomplished from the exterior of the camera by a key 13, (see Figs. 2 and 3), which is limited in its movements by stop projections 14, formed on a plate 15, secured to the camera and through which said key passes. This key has a bifurcated inner end which engages a bail 16, secured to the magazine section 9. Of course, it will be understood, by referring to Fig. 2, that there is one of such keys for each magazine, and that the magazines are of the same construction, and therefore, interchangeable.

As shown, the magazine 4 contains the supply reel and the magazine 5 the rewind reel, which is driven by a belt 17, leading from a belt pulley 19 on the power shaft of the machine to a pulley 18 screw-threaded on the end of the film reel spindle.

The complete series of operations and functions of the devices and attachments hereinbefore described in detail will now be described with respect to their sequential performance. One or more camera film magazines are loaded, in a dark room, with reels of sensitized film, the magazine section 9 being turned to close the film opening 12, allowing the film to thread through the film aperture of the inner section 8, then circumferentially between the walls of both sections and out the film aperture of the outer section 9.

Film magazines containing an empty film reel and one of the loaded magazines are mounted on the uprights 3, as shown in Fig. 1, with the empty reel in driving connection with the power shaft. The film is threaded through the film controlling provision and to the rewind reel after which the cover 2 is positioned and latched on the base 1. The key 13 adjacent the loaded reel magazine 4 is then pushed inwardly to engage and turn the magazine section 9 thereof to bring the film apertures into registry.

After the film of the loaded reel is exposed and rewound on the driven reel, the key 13 adjacent the magazine 5 is turned to close the film opening 12 thereof, after which the cover 2 is removed to change the magazines. The magazine 5, now containing a full reel of exposed negative film, is removed from the camera, the magazine 4, now containing an empty reel, being re-

positioned on the uprights 3 to assume the position previously occupied by magazine 5, and a new, previously loaded magazine placed in position as magazine 4. The film is again threaded through the camera and parts positioned, as above described.

I claim—

1. In a device of the class described, a light-proof casing formed with a film passage, axially telescoping magazine members mounted in said casing and having registering film apertures, the area of which is fixed by circumferentially relatively adjusting said telescoping members, rotatable means for supporting the film within said telescoping members, and means exterior of the light-proof casing for adjusting the magazine members to control the area of said registering film apertures.
2. In a device of the class described, a film magazine comprising a first section and a second section concentrically telescoping rotatively about the axis of the first section, the sections being peripherally coincidentally apertured for film passage, a reel supporting spindle secured to the first section, a film reel journaled thereon, means exterior of the sections as a unit, for driving the reel, and means connected to the second section straddling the axis of the reel for rotating said second section.
3. In a device of the class described, a film magazine comprising a first magazine section and a second relatively rotative magazine section telescopically united, the sections being peripherally coincidentally apertured for film passage, a film reel concentrically journaled in the magazine, means exterior of the magazine for driving said reel and key coupling devices connecting with the second section to control the aperture area of the magazine.
4. In a device of the class described, a camera casing, a film magazine supported therein and comprising relatively a stationary section and an axially telescoping rotative section, both sections being peripherally coincidentally apertured for film passage, means exterior of the camera casing for adjusting the rotative section to control the aperture area, a film reel rotatively journaled in the magazine and a driving element operatively connected thereto, exterior of the magazine.
5. In a device of the class described, a camera casing, a film magazine supported therein and comprising relatively a stationary section and an axially telescoping rotative section, both sections being peripher-

ally coincidentally apertured for film passage, means exterior of the camera casing for adjusting the rotative section to control the aperture area, and means for limiting said adjusting movement, a film reel journaled in the magazine and a driving element operatively connected thereto concentrically, exterior of the magazine.

6. In a device of the class described, a camera casing, a pair of opposing film magazines relatively angularly supported therein and peripherally apertured for film passage, a film reel journaled within each magazine, and a driving means operatively connected to one of the film reels exterior of the magazine.

7. In a device of the class described, a film magazine comprising a first section and a second relatively rotative section telescopically united, the sections being peripherally coincidentally apertured for film passage, a film reel journaled within the magazine and having a spindle projecting through the rotative section, and driving means detachably secured to said reel spindle exterior of the sections as a unit.

8. In a device of the class described, a film magazine comprising a first section and a second relatively rotative section telescopically united, the sections being peripherally coincidentally apertured for film passage, a film reel journaled within the magazine and having a spindle projecting through the rotative section, driving means detachably secured to said reel spindle exterior of the sections as a unit, and hand-hold means detachably connected to the second section for rotating the same.

9. In a device of the class described, a camera casing, a pair of uprights mounted therein, a film magazine comprising a non-rotative section provided with projections meshingly engaging said uprights and a relatively rotative section telescopically united, both sections being peripherally coincidentally apertured for film passage, a film reel journaled within the magazine, means exterior thereof for driving the reel, and means exterior of and projecting into the camera casing to engage and adjust the rotative section to control the aperture area.

In witness whereof, I hereunto subscribe my name, as attested by the two subscribing witnesses.

JOHN T. WELLS.
